DESIGN FOR A HEARING AID UNIT

Harold W. Darr, Minneapolis, Minn., assignor to
The Maico Company, Incorporated, Minneapolis,
Minn., a corporation of Minnesota

Application September 16, 1944, Serial No. 115,319

Term of patent 7 years

(Cl. D26—14)

To all whom it may concern:

Be it known that I, Harold W. Darr, a citizen of the United States, residing at Minneapolis, in the county of Hennepin and State of Minnesota, have invented a new, original, and ornamental Design for a Hearing Aid Unit, of which the following is a specification, reference being had to the accompanying drawing, forming part thereof.

Referring to the drawing:

Fig. 1 is a front elevational view of a hearing aid unit showing my new design; and
Fig. 2 is a side elevational view thereof.

The back of the unit is plain.

I claim:

The ornamental design for a hearing aid unit, substantially as shown and described.

HAROLD W. DARR.
